ADJUSTABLE BOWDEN WIRE

William W. Lasker, Brooklyn, N. Y., assignor to
 Remington Rand Inc., Buffalo, N. Y., a corporation of Delaware

Application December 17, 1934, Serial No. 757,906

5 Claims. (Cl. 74—502)

This invention relates to Bowden wires and, more particularly, to an adjustable Bowden wire for connecting and operating parts of machines in which it is necessary that the wires be bent sharply at a plurality of points, to pass around obstructions or to permit the connection of two parts of a machine which are not in the same plane.

It is a well known fact that, when a Bowden wire is bent sharply at a plurality of points, such as an S-curve, the casing is elongated. This is due to the enlarging of the interstices between the spirals of the casing. When these interstices are enlarged to any great extent, the casing is elongated and the free end of the push or drive wire is covered.

It is, therefore, the principal object of this invention to provide a Bowden wire having a casing which may be adjusted to compensate for any variations in length thereof.

A further object is to provide an easily and positively adjustable Bowden wire casing which will permit a variation of the length of the casing without disturbing the ends thereof.

A still further object is to provide an adjustable coupling member for a Bowden wire casing which is simple and easily manufactured.

Further objects and structural details of the invention will be apparent from the following detailed description taken in conjunction with the accompanying drawing, in which:

Fig. 1 discloses a Bowden wire embodying the invention.

Fig. 2 is an enlarged cross section of the mid-portion of Fig. 1 disclosing the parts in their maximum adjusted position.

Fig. 3 is an enlarged cross section of the mid-portion of Fig. 1 disclosing the parts in their minimum adjusted position.

Fig. 4 discloses the parts of Fig. 1 separated.

Fig. 5 is an enlarged cross section of the top portion of Fig. 1.

Fig. 6 is an enlarged cross section of the bottom portion of Fig. 1.

The invention, as disclosed in Fig. 1, comprises a flexible casing 2 of the well known type in use on Bowden wires. Secured to the upper end of the casing by any well known means, such as swaging or sweating, is a cylindrical member 3.

The upper end of the member 3 is threaded to permit the attachment of the casing to the machine with which the Bowden wire is to be used.

Positioned in the cylinder is a plunger 4 formed as shown in Fig. 5, which extends beyond the casing and has a shoulder 5 formed on the inner end

thereof. Positioned between the head of cylinder 3 and shoulder 5 is a spring 6 for maintaining the plunger 4 in a withdrawn position. A push wire 7 is secured in the bottom of the plunger 4 in any well known manner and extends through the casing.

The other end of casing 2 is secured in a threaded sleeve 8 which is one-half of the adjustment device of the invention. This sleeve is formed as shown in Figs. 2 and 4, the bore of the sleeve being restricted by a shoulder 9 formed in the lower end thereof. Positioned in sleeve 8 is a plunger 10 having a hole formed in one end thereof for accomodating the free end of push wire 7. The shoulder 9 restricts and prevents the movement of plunger 10 out of the sleeve 8. It is apparent that the cylinder 3, casing 2, and threaded sleeve 8 form one self-contained unitary portion of a Bowden wire.

The other or lower end of Fig. 1 discloses a cylinder 11, similar to that described above, which is secured to casing 12. Positioned in cylinder 11 is a plunger 13 formed as shown and having a push wire 14 secured thereto.

The other end of the casing 12 is secured to a sleeve 15, formed, as shown in Fig. 2, with a collar 16. Positioned about sleeve 15 and limited by the collar 16 is an internally threaded sleeve 17. The sleeve 17 is held in position on sleeve 15 by a threaded bushing 18 having a slot 19 cut in the top thereof for enabling a screw driver to be used in assembling the parts. The sleeve 15 is assembled with sleeve 17 by dropping sleeve 15 into sleeve 17 and then screwing the bushing 18 down on to the collar 16, thereby preventing the sliding of sleeve 15 on sleeve 17. Sleeve 17 is threaded only a predetermined distance to prevent the bushing 18 from being screwed down tight on to the collar 16. This is done to permit the sleeve 17 to turn freely on sleeve 15, thereby preventing any twisting of the casing 12 when sleeve 17 is screwed on to sleeve 8. Positioned in sleeve 15 is a plunger 20 formed as shown, and having a hole formed in the end thereof to accommodate push wire 14.

In assembling the two portions of the invention, the sleeve 17 is screwed on to the sleeve 8 until the end of plunger 20 comes into contact with plunger 10, as shown in Fig. 3. Any further turning up of the sleeves one on the other until the extreme adjustment is reached, as shown in Fig. 2, will force plunger 10 upward in casing 2 and elongate the exposed portion of plunger 4. A knurled lock nut 21 is provided which locks the two sleeves 8 and 17 in their adjusted position.

It is apparent that a Bowden wire having the adjustable features of the invention has many uses such as in remotely controlled gauges, selecting devices such as card sorting business machines 5 and for connecting separate units of machinery such as the base and head of a tabulating business machine. It is obvious that there are many other uses which are too many to enumerate.

A device of this character has another novel 10 feature, namely, that of variably and selectively interconnecting a plurality of units to a distant plurality of units. For example, a Bowden wire of this type may be used in a lace making loom to interconnect the pattern sensing pins and the 15 shuttles. It is apparent that this interconnection may be varied by merely disconnecting the wires in the center and reconnecting in any other manner desired without taking the whole wire out of the machine.

20 While I have described what I consider to be a highly desirable embodiment of my invention, it is obvious that many changes in form could be made without departing from the spirit of my invention, and I, therefore, do not limit myself 25 to the exact form herein shown and described, nor to anything less than the whole of my invention as hereinbefore set forth, and as hereinafter claimed.

What I claim as new and desire to secure by 30 Letters Patent, is:

1. In a device of the character described, a central wire, a flexible casing therefor, an adjustable union intermediate the ends of said casing, said wire being formed in two parts, the ends of each 35 part having plungers secured thereto, one end of each part of said wire being positioned in the component parts of said union, and means in said union for varying the length of one of said casings with respect to its associated wire.
2. In a device of the character described, a pair 40 of central wires, a flexible casing for each, an adjustable coupling for operatively connecting said wires and casings together, a plunger operatively connected to the adjacent ends of said wires, said plungers being movably positioned in abutting relation in the component parts of said coupling, and means for varying the length of one of said casings with respect to its associated wire.

55

atively connected to the ends of each of said wires, one of said plungers on each wire being movably positioned end to end in the component parts of said coupling, and means for varying the length of one of said casings with respect to its associated wire.

3. In a flexible connecting device of the character described, a pair of central wires, flexible casings therefor, an adjustable coupling for securing said casings together, a plunger operatively connected to each end of said wires, one of said plungers on each wire being movably positioned end to end in the component parts of said union, and means for varying the length of one of said casings with respect to its associated wire, said 15 means comprising an internally threaded sleeve, an externally threaded sleeve, one being adapted to be screwed into the other and a lock-nut for maintaining said sleeves in adjusted relation.

4. In a device of the character described, a pair 20 of central wires, a flexible casing for each, an adjustable coupling for operatively connecting said wires and casing together, a plunger operatively connected to the adjacent ends of said wires, said plungers being movably positioned in abutting 25 relation in the component parts of said coupling, and means for varying the length of said casings with respect to its associated wire.

5. In a connecting device of the character described, a pair of central wires, a flexible casing 30 for each, an adjustable coupling for securing said casings together, a plunger operatively connected to the adjacent ends of said wires, said plungers being movably positioned in abutting relation in the component parts of said coupling, and means 35 for varying the over all length of said casings with respect to the associated wires, said means comprising an internally threaded sleeve, an externally threaded sleeve, the first being adapted to be screwed into the second and a lock nut for 40 maintaining said sleeves in adjusted relation.

WILLIAM W. LASKER.
